UNITED STATES PATENT OFFICE.

JOHN G. McNABB, OF CHICO, CALIFORNIA.

MAIL-BOX.

1,172,619.

Specification of Letters Patent. Patented Feb. 22, 1916.

Application filed January 7, 1915. Serial No. 1,005.

To all whom it may concern:

Be it known that I, JOHN G. McNABB, a citizen of the United States, residing at Chico, in the county of Butte and State of California, have invented certain new and useful Improvements in Mail-Boxes, of which the following is a specification.

This invention relates to receptacles for mail matter, more particularly to receptacles employed in connection with the rural free delivery system, and it has for one of its objects to improve the construction and increase the efficiency and utility of a device of this character.

Another object of the invention is to provide a simply constructed device in which mail may be readily inserted, but from which it can be taken only through the discharge opening which is protected by a locked door, thus preventing any surreptitious removal of the mail.

Another object of the invention is to provide a simply constructed device which is automatically retained in receiving position, and in which the receiving member is automatically returned to receiving position after the deposit of each piece of mail.

With these and other objects in view, the invention consists in certain novel features of construction hereafter shown and described and then specifically pointed out in the claims; and in the drawings illustrative of the preferred embodiment of the invention, Figure 1 is a perspective view of the improved device. Fig. 2 is a longitudinal sectional elevation. Fig. 3 is a section on the line 3—3 of Fig. 2.

Corresponding and like parts are referred to in the following description and indicated in all the views of the drawings by the same reference characters.

The improved device comprises a shell or casing, represented as whole at 10, and with a rounded or semi-cylindrical top 11. The body portion 10 is provided with a relatively large opening 12 in one side covered by a door 13 preferably hinged at 14 to the body and provided with a means, such as a hasp and staple 14' for receiving a suitable lock. Mounted for rotation through the upper portion of the casing, and preferably centrally of the semi-cylindrical top 11, is a shaft 15 having an operating crank 16 at one end externally of the casing. Mounted to rotate with the shaft 15 is a mutilated cylindrical member 17 closed at the ends

having an angular cavity 18 in one side, the cavity being preferably located opposite the crank 16, the crank being thus utilized as a counter-weight to hold the member 17 with its cavity 18 upwardly, as illustrated in Fig. 3. An opening 19 is formed in the end of the semi-cylindrical shell 10 and communicating with the cavity 18 of the member 17, as illustrated in Figs. 1 and 2. By this means when the crank 16 is at rest or in downward position, as indicated in Figs. 1 and 2, the cavity 18 will be located opposite the opening 19 so that mail matter may be thrust through the opening 19 into the cavity 18. Then by rotating the crank 16 in either direction the mail matter will be dumped into the lower portion of the shell or receptacle. When the cylindrical member is overturned to discharge the contents, the imperforate portion of the end next to the receiving opening will close the receiving opening and still further protect the contents of the receptacle. The coaction of the unmutilated portion of the member 17 and the semi-cylindrical portion 11 effectually prevents surreptitious access to the mail matter through the opening 19. The shaft 15 is preferably supported by washers 20 within the member 17 to increase the strength and durability of the device.

The shell 10 and its adjustments may be of any required size and of any suitable material, and it is not desired, therefore, to limit the invention in any manner in this respect.

The receptacle and its attachments may be supported in any suitable manner upon a post, fence, building or other support, but as the support forms no part of the present invention it is not deemed necessary to illustrate the same.

The curved upper portion 11 of the casing is extended at the end having the opening 19 to form a guard over the opening, and a closure 21 is hinged at 22 to the extension to protect the interior of the receptacle from the elements.

Having thus described the invention what is claimed as new is:

1. A device of the class described comprising a receptacle having a semi-cylindrical top and a receiving opening in one end, a shaft mounted for rotation through said receptacle, a cylindrical member mounted to rotate with said shaft and in close engagement with the semi-cylindrical top of

the receptacle and having a cavity in one side, and a crank carried by said shaft and maintaining the cavity of said cylindrical member normally in registering relation with the receiving opening of said receptacle and adapted to operate the cylindrical member in either direction.

2. A device of the class described comprising a receptacle having a semi-cylindrical top and vertical ends and a receiving opening in one of said ends, a shaft mounted for rotation through said receptacle, a cylindrical member closed at the ends and mounted to rotate with said shaft, said cylindrical member operating in close engage-

ment with the semi-cylindrical top of the receptacle and having a cavity in one side and in one end thereof, and a crank carried by said shaft and maintaining the cavity of said cylindrical member normally in registering relation with the receiving opening of said receptacle and adapted to operate the cylindrical member in either direction. 20

In testimony whereof I affix my signature in presence of two witnesses.

JOHN G. McNABB. [L. s.]
